UNITED STATES PATENT OFFICE.

FREDRICK F. BIOREN, OF NEWARK, NEW JERSEY, ASSIGNOR TO BIOREN BROTHERS, OF SAME PLACE.

SLEEVE-BUTTON.

SPECIFICATION forming part of Letters Patent No. 254,087, dated February 21, 1882.

Application filed January 10, 1882. (No model.)

To all whom it may concern:

Be it known that I, FREDRICK F. BIOREN, a resident of Newark, in the county of Essex and State of New Jersey, have invented certain 5 new and useful Improvements in Sleeve-Buttons; and I do hereby declare the following to be a full, clear, and exact description of the invention, such as will enable others skilled in the art to which it appertains to make and use 10 the same, reference being had to the accompanying drawings, and to letters of reference marked thereon, which form a part of this specification.

The object of this invention is to reduce the 15 cost of non-separable cuff and collar buttons, to facilitate the operation of the same, and to render the device more durable.

The invention consists in the arrangement and combination of parts, all as will be hereinafter set forth, and embodied in the claims.

Referring to the accompanying drawings, in which similar letters of reference indicate like parts in each of the several figures, Figure 1 is an elevation of a sleeve-button embodying 25 my invention; Figs. 2 and 3, sections of the same, taken through line *x*, showing the shoe in two positions, the first adapting the button to secure the cuff, and the second adapting the shoe to be thrust through the button-holes. 30 Figs. 4 and 5 are views of detached portions of the button, and will be explained more definitely hereinafter.

In carrying out my invention I construct the body *a* of the button in any usual manner, and 35 attach, by means of solder or otherwise, a shank, *b*, having a slot, *c*, therein terminating near the outer end of the shank, where is formed a cross-head, *d*, as shown in Fig. 4. I then form a cross-bar, *e*, having a transverse groove, *f*, adapted 40 to engage with said cross-head *d*, and having a lug, *g*, projecting from said cross-bar on the side opposite said transverse groove. The bar *e* is then passed into the slot *c*, and the groove *f* brought into engagement with the cross-head 45 *d*, after which the shoe *h* is attached (by means of solder or by returning the edge of said shoe over the ends of said cross-bar, as shown in Figs.

2 and 3, or by other appropriate means) to the face *e'* of the cross-bar. A spring, preferably flat, is then riveted or otherwise secured to the lower portion of the shank *b*, so that it will bend back through the slot, and its free end will have a tendency to fly forward. Said free end of the spring engages with and bears against a flat side of said lug and tends to hold the same in a fixed position, as shown in the 55 sectional figures, and as will be clearly understood.

By this construction the button can be manufactured with comparative cheapness, while its 60 facility of operation is apparent.

Having thus described my invention, what I claim, and wish to secure by Letters Patent, is—

1. In a button, the combination, with the 65 slotted shank, having a cross-head, *d*, thereon, of a cross-bar pivoted thereon, having a lug, *g*, and a spring secured to the face of the shank engaging with said lug, the whole being arranged and operating substantially as and for 70 the purposes set forth.

2. The combination, in a button, of the slotted shank, the spring secured to the face of said shank, and the cross-bar, having a projecting lug working in said slotted shank and engaging with said spring, all being arranged and operating substantially as and for the purposes 75 set forth and shown.

3. The combination, with the body *a* and shoe *h*, of the slotted shank secured to said 80 body, the cross-bar pivoted on said shank and secured to said shoe, and the spring secured upon the face of the shank and bent backward through the slot therein and bearing forward against the lug, all substantially as and for the 85 purpose set forth and shown.

In testimony that I claim the foregoing I have hereunto set my hand this 5th day of January, 1882.

F. F. BIOREN.
